UNITED STATES PATENT OFFICE.

NORMAN W. TUMBLINSON, OF BALTIMORE, MARYLAND.

HANDLE ATTACHMENT FOR DUST-PANS.

1,257,552.

Specification of Letters Patent. Patented Feb. 26, 1918.

Application filed March 15, 1917. Serial No. 154,960.

To all whom it may concern:

Be it known that I, NORMAN W. TUMBLINSON, a citizen of the United States, residing at Baltimore city, in the State of Maryland, 5 have invented certain new and useful Improvements in Handle Attachments for Dust-Pans, of which the following is a specification.

This invention relates to a handle attachment for dust-pans.

The ordinary dust-pan for receiving floor-sweepings and dust, usually has a short handle which, when the pan is being used on a floor, requires a person to stoop over or 15 squat; this posture is uncomfortable and inconvenient.

The object of the present invention is to provide for the ordinary short-handle dust-pan, a relatively long-handle which has self-acting means for attachment to the dust-pan and enables a common dust-pan to be used 20 while a person is in a standing position.

This improved long-handle attachment for dust-pans, does not grip the usual short-handle with which the pans are provided, but has a wire-clip that engages the back-wall 25 of the dust-pan.

The invention is illustrated in the accompanying drawing in which,—

Fig. 1, is a side view of a dust-pan having an ordinary short handle, and shows the long-handle of this invention attached to 30 the pan.

Fig. 2, shows the back-wall of a dust-pan with the improved long handle attached thereto.

Fig. 3, in this view the parts on a little larger scale, are shown on a vertical broken line 3—3 of Fig. 2.

Fig. 4, is a perspective view on a larger scale than in Figs. 1 and 2, and shows the long handle and the wire-clip that engages the handle with the dust-pan.

Referring now to the drawing the numeral, 5, designates the body-part of an ordinary dust-pan of a type that is well known; 6, is the usual short handle of such dust-pans and projects rearward from the back-wall, 7, which latter has a stiff top-edge, 8.

The improved long handle device comprises a straight rod, 9, which, at one end, carries the wire-clip. The handle rod may consist of metal, wood or other material.

55 The shank, 10, of the wire-clip consists, in the present instance, of two ends of a wire

which converge to a point like a V, and the two ends enter the end of said handle rod and are made fast therein.

The wire clip also has a central loop of 60 inverted U formation, designated, 11, which stands upright and the open end of the U faces downwardly and straddles the short handle, 6, of the dust-pan, and when applied to the dust-pan this upright part has 65 position adjacent to the back-wall, 7, of the pan, see Fig. 2. The clip has two double-back bends, 12, one at each side of the central loop and each of which is inclined forwardly and downwardly, in a direction away 70 from the shank, 10, and points into the dust-pan. Said bends, 12, take over and engage the top rear edge, 8, of the back-wall, 7, of the dust-pan as in Figs. 1 and 2, and the two together serve as the upper side of the wire 75 clip device. Immediately below each doubled-back bend, 12, is a reverse doubled-back bend, 13, that points upwardly and backwardly and its shape conjointly with the double-back bend, 12, produces an open 80 slot, 14, that receives the top edge, 8, of the dust-pan wall, 7.

From each reverse doubled-back bend, 13, a bar, 15, extends downwardly; each of these wire bars, 15, then extend forward at a 85 right-angle and thereby form two horizontal parallel loops, 16, that are spaced apart and which are connected by the central inverted loop 11.

When looking at the back-wall 7, as in 90 Fig. 2, the inverted U wire device is seen straddling the short handle, 6; and at each side of the handle one of the down bars, 15, is also seen. It will be understood the two horizontal loops, 16, both take position at 95 the lower side of the pan bottom and said loops serve as the lower side of the clip device. The wire parts are slightly yielding or springy.

By holding the dust-pan firmly in one 100 hand, a person with his other hand grasping the aforesaid wire parts, may cause the same to yield enough to be slipped on the wall of the pan, or detached therefrom. No screws or nuts are used.

105 From the foregoing description and an inspection of the drawing, it will be understood that the two ends of a wire are suitably attached to the handle-rod, and the portion of the wire intermediate of said two 110 ends forms a top-engaging or rim-engaging device and a bottom-supporting device which

clip onto or take hold of the dust-pan, and hold it securely.

Having described my invention, what I claim and desire to secure by Letters Patent is,—

An attachment for handled dust-pans comprising a wire having two ends which merge into a handle and the intermediate portions of said wire being bent to form two spaced apart parallel loops which are connected by an intermediate loop,—the intermediate loop extending in a direction at an

angle with respect to the two loops it connects and the wire at a point between each of the two parallel loops and its ends being bent to form inclined slots to receive the rear rim edge of a dust-pan.

In testimony whereof I affix my signature in the presence of two witnesses.

NORMAN W. TUMBLINSON.
